CLAIM

The ornamental design for an aerial, as shown and described.

DESCRIPTION

FIG. 1 is a front view of the aerial showing our new design in a closed (lowered) position, the rear, left and right side views being identical save for the rotation of treads;

FIG. 2 is a perspective view thereof;

FIG. 3 is a top view thereof;

FIG. 4 is a bottom view thereof; and,

FIG. 5 is a front view thereof with the aerial in an open position, the rear, left and right side views being identical save for the rotation of treads.
